ELBOW FOR WIRING CONDUITS

Original Filed Aug. 1, 1922

INVENTOR
Joseph A. Volk Jr.
BY
Geo. Scherr Jr. ATTORNEY

UNITED STATES PATENT OFFICE.

JOSEPH A. VOLK, JR., OF NORWALK, CONNECTICUT, ASSIGNOR TO THE VECO MFG. COMPANY, A CORPORATION OF CONNECTICUT.

ELBOW FOR WIRING CONDUITS.

Application filed August 1, 1922, Serial No. 578,974. Renewed December 18, 1923.

To all whom it may concern:

Be it known that I, JOSEPH A. VOLK, Jr., a citizen of the United States, and resident of Norwalk, in the county of Fairfield and State of Connecticut, have invented certain new and useful Improvements in Elbows for Wiring Conduits, of which the following is a specification.

My present invention relates to improvements in elbows for wiring-conduits having an opening through its wall for readily drawing the wires through one conduit to which the elbow is attached and passing them through the other conduit connected by the elbow to the first named conduit, whereby one and the same elbow is adapted to be used universally in practically any corner or position of the installation with the said opening always accessible. Also means is provided whereby the screw-holes and the contained screws for fastening the cover over said opening always make the heads of the screws incline away from the adjacent wall, floor or ceiling, etc., so as to be readily accessible to a screw-driver; furthermore, the adaptation is such that the screws cannot contact with or injure the contained wiring.

The drawings show one preferred embodiment of my invention. In them, Fig. 1 is a side elevation of my improved elbow with the internal structure indicated by dotted lines; Fig. 2 is an end elevation of same looked at from the left in Fig. 1; Fig. 3 is a plan view as seen from the top in Fig. 1; Fig. 4 is a perspective view of the cover detached from the elbow; Fig. 5 is a horizontal section on the line 5—5 in Fig. 1 combined with a plan view of the rest of the elbow; and shows also a conduit screwed into one end of said elbow; Fig. 6 is a vertical section on the line 6—6 in Fig. 1 combined with an elevational view of the rest of the elbow; and shows also a conduit screwed into the vertical arm of the elbow; Fig. 7 is supposed to show in plan the floor and the four walls of a room and illustrates how my elbow fitting (made in one style like Fig. 1, without any right or left) can be used in any corner of the room and yet have the cover-opening to the front with said opening accessible to get at the wires within and also with the screws accessible for attaching and detaching the cover; Figs. 8, 9 and 10 are respectively combined cross-

sectional and elevational views on the section-lines of the same numbers in Fig. 7.

Describing now my invention as illustrated by the particular embodiment thereof in the drawings, 1—1 are the usual electrical wiring-conduits adapted to be connected together by my improved elbow 3. The ends of said elbow are internally screw-threaded at 4 to receive the threaded ends of the conduits.

Externally, the ends of the elbow are preferably formed with integral flat portions 5 adapted to be engaged by a wrench.

The side of the elbow has an opening through it adapted to be closed by the cover 7. Both the elbow with its said opening and also said cover 7 are in practice molded as separate pieces but for the purpose of describing the position and nature of the opening and the shape of the cover, the same 75 may be described as having been formed by an inclined cut taken through the side of an ordinary pipe elbow, said cut beginning on the outside of the elbow near the bend 8 (Fig. 1) and inclining inwardly toward the 80 point 9 (Figs. 1 and 2) of the elbow.

The described opening is such that not only can the electrician get access through it to the wires of one conduit to draw them taut and pass them through the other conduit, but also one and the same elbow with said kind of opening is adapted to be used universally in practically any corner or position in the installation with said opening outermost and giving access to the interior 90 of the elbow and the related conduits.

How this is possible is shown in Fig. 7, showing in plan the floor and the four walls of a room with one of my elbows located in each corner of the room with its side-opening away from (as distinguished from against) the wall and therefore fully accessible. In all of the figures, I have designated the same end of the elbow by the letter A and the opposite end by B. By noting these lettered ends of the elbows in Fig. 7, it will be seen how the elbow can be shifted in its position to fit each and every corner and yet still bring its opening to the outside for ready access. Accordingly, no rights 100 and lefts (meaning two kinds of elbows, one with openings on the left side and the other with openings on the right side) are necessary, the inconvenience and expense of having two or more kinds of elbows being saved 110

2
due to the described construction of my
elbow.

5 The cover 7 is fastened in place by means
of screws 10 which are tapped tangentially
into the walls of the elbow, which walls for
this purpose are thickened internally by
transversely extending integral ribs 11 on
the inside of the elbow. These screws are
thereby located wholly inside said rib-
10 thickened walls and, therefore, cannot injure
the insulation of the contained wires;
nor do they obstruct the interior of the
elbow except to the slight immaterial ex-
tent equal to the thickness of said ribs.

15 Furthermore, it will be noted from the
various figures that said screw-holes are
tapped in said walls in directions such that
in whatever corner the elbow may be lo-
cated, each of the two screws inclines from
20 its point to its head away from the adjacent
wall, floor or other surface. This makes it
easy to use a screw-driver to attach or de-
tach the cover when the elbow is located in
a corner.

25 In short, my improvements in elbow fit-
tings give same decided advantages. Some
of said improvements may be used without
others. Also, changes and modifications may
be made in the practical embodiments of my
30 present improvements which will, neverthe-
less, still be within the spirit of the fore-
going description and within the meaning and
spirit of the annexed claims and which as
such are accordingly intended to be covered
35 thereby.

What I claim is:

1. An elbow for connecting wiring-con-
duits having an opening through its side for
40 access to its interior, the plane of the mouth
of said opening beginning on the outside of
the elbow near the bend and inclining in-
wardly towards the point of the elbow.

45 2. An elbow for connecting wiring-con-
duits having an opening through its side for
access to its interior, the plane of the mouth
of said opening beginning on the outside of
the elbow near the end and inclining in-
wardly towards the point of the elbow; and
a detachable cover for said opening.

50 3. An elbow for connecting wiring-con-
duits having an opening through its side for
access to its interior, the plane of the mouth
of said opening beginning on the outside of
the elbow near the bend and inclining in-
wardly towards the point of the elbow; a
cover for said opening; and means for fas-

tening said cover to the elbow comprising a
transversely extending integral rib on the
inside of the elbow, said rib being length-
wise tapped with screw threads adapted to
be engaged by a screw for fastening the
cover to the elbow.

55 4. An elbow for connecting wiring-con-
duits having an opening through its side for
access to its interior, the plane of the mouth
of said opening beginning on the outside of
the elbow near the bend and inclining in-
wardly towards the point of the elbow; a
cover for said opening; and means for fas-
tening said cover to the elbow comprising a
70 screw-threaded opening tapped substantially
tangentially in the wall of the elbow adapted
to be engaged by a screw for fastening the
cover to the elbow.

75 5. An elbow for connecting wiring-con-
duits having an opening through its side for
access to its interior; a cover for said open-
ing; and means for fastening said cover to
the elbow comprising a screw-threaded open-
ing tapped substantially tangentially in the 80
wall of the elbow in a direction such that
said opening inclines from its inner to its
outer end away from the adjacent wall or
surface of a corner in which the elbow may
be located with its aforesaid side-opening
85 disposed accessibly outward.

90 6. An elbow for connecting wiring-con-
duits having an opening through its side for
access to its interior; a cover for said open-
ing; and means for fastening said cover to
the elbow comprising a transversely extend-
ing integral rib on the inside of the elbow,
95 said rib being lengthwise tapped with screw-
threads adapted to be engaged by a screw
for fastening the cover to the elbow.

100 7. An elbow for connecting wiring-con-
duits having an opening through its side for
access to its interior; a cover for said open-
ing; and means for fastening said cover to
the elbow comprising a substantially tangen-
tial opening in the wall of the elbow in a
105 direction such that said opening inclines
from its inner to its outer end away from the
adjacent wall or surface of a corner in which
the elbow may be located with its aforesaid
side-opening disposed accessibly outward;
and means received into said opening for
fastening said cover.

Signed at New York in the county of New
York and State of New York this 31st day
of July A. D. 1922.

JOSEPH A. VOLK, JR.
